DOOR LOCK

Harry E. Fendring, Los Angeles, Calif., assignor to
A. Ferstat di Valvasone

Application October 4, 1941, Serial No. 413,642

9 Claims. (Cl. 292—254)

My present invention relates to locks for doors and the like.

One of the principal objects of this invention is to provide a door lock in which the locking bolt, which is usually provided in the door itself, is constructed to be mounted in the door jamb, and also to provide a lock in which the lock is so constructed that the bolt-receiving opening is normally closed or covered when the door is open.

Another important object of this invention is to provide a lock which is so constructed that a bolt-ejector in the keeper is resiliently held flush with the face of the keeper, and which serves as a shock absorber when the bolt enters the keeper opening, resulting in absorption of the shock when the outwardly forced bolt enters the keeper opening, thereby resulting in an extremely silent lock.

An important object also of this invention is to provide a lock in which the spindle for the lock operating member is entirely separate from the lock mechanism, or lock-ejecting mechanism, thereby providing a lock which may be readily installed without the necessity of accurately aligning the spindle with the other portion of the mechanism.

A still further important object of this invention is to provide a compression lock which is so constructed and arranged that it may be made largely of plastic materials, or from what is known as, plastics.

A further object of this invention is to provide a door lock having a novel and simple locking mechanism at one side of a door, and also novel means for unlocking the same from the opposite side.

A still further object of this invention is to provide a door lock which on the whole is very simple and economical of construction, durable, and which will not readily deteriorate or get out of order.

With these and other objects in view, I have devised a door lock having certain novel features of construction, combination, and arrangement of parts and portions, as will be hereinafter described in detail and particularly set forth in the appended claims, reference being had to the accompanying drawing and to characters of reference thereon, which form a part of this application, in which:

Fig. 1 is a fragmentary sectional view in plan of a door jamb and the corresponding free-edge of a door, showing portions of my locking mechanism mounted in each;

Fig. 2 is a similar sectional view thereof with the door in a closed position, but showing portions of the mechanism broken away;

Fig. 3 is an elevational view taken, at 3—3 of Fig. 2 showing the outside of the bolt and bolt housing in the door jamb;

Fig. 4 is an elevational view of the free edge of the door; and,

Figs. 5, 6, and 7, are sectional views taken respectively, through 5—5, 6—6, and 7—7, of Fig. 2.

One of the principal objects of this invention is to provide a door lock which may be readily and economically made of a plastic material, and the following description of my lock will be more readily understood if such construction is kept in mind.

The door bolt 1 is of rectangular cross-section, or of round cross-section with a flattened side, and is reciprocally mounted in a housing 2 which may also be of similar cross-section. The hollow portion 2^a of the housing in which the bolt reciprocates, is inserted in a round hole J^a of the jamb J. The housing is provided with a securing plate 2^b at its outer end, whereby the housing may be secured to the door jamb, by screws 3. The bolt 1 is forced outwardly, so that its outer end extends beyond the securing plate 2^b, by means of a compression spring 4. The spring is positioned around the reduced shank 1^a of the bolt, which extends backwardly from the outer portion, and between the inner end of the outer portion of the bolt and the inner end of the hollow portion 2^b of the housing. The bolt is held in place, or limited in its outward movement, by a shoulder at the inner end of the shank 1^a. This shoulder is formed by means of a collar 5 which is secured to the shank by means of acetone, this collar being held in engagement with the inner end of the housing 2, by the spring 4.

The outer end of the bolt is bevelled or rounded, as in the usual bolt construction.

The elements of the above bolt construction are made of plastic except the screws 3 and the spring 4.

In the free edge of the door D is provided a keeper 11 having an opening 11^a for receiving the bevelled portion of the bolt. The forward portion of the keeper, which normally engages the bolt, is slightly rounded, providing the strike plate portion 11^b. This keeper or strike plate is secured in position in the free edge of the door by screws 12. The keeper or strike plate has an inwardly extending tubular ejector housing 13, in which is reciprocally mounted the ejector 14.

This ejector housing is inserted into a hole D¹ at the edge of the door D.

The keeper opening 11^a is coincident with or is located at the outer end of the bore or interior 13^a of the housing 13. The head 14^a of the ejector 14 may be of a cross-section similar to but slightly larger than the bolt and is normally located within the keeper opening 11^a. The head of the ejector is adapted to enter the outer end of the bore 13^a. The ejector has a centrally located and backwardly extending tubular shank 14^b. Near the inner end of the bore is a constricted portion or wall 13^b having a circular hole through which the shank 14^b extends. The opposite sides of this constricted portion provide shoulders, as will be described hereinafter. Around the shank 14^b is a compression spring 15 which is located between the head 14^a and the adjacent shoulder of the wall 13^b. The spring 15 urges the outer face of the head flush with the outer side of the keeper or strike plate. Such outer position of the ejector is limited by a collar 14^c near the inner end of the shank 14^b, this collar engaging the inner side of the shoulder of the wall 13^b.

The compressive strength of the spring 15, when the ejector is forced outwardly, may be approximately two ounces (2 oz.), and, when forced inwardly by the bolt, it is approximately five ounces (5 oz.). The normal expanded compressive strength of spring 4 is slightly greater, and may be six ounces (6 oz.). Thus, the spring 15 will be compressed by the spring 4, but the ejector will absorb the shock of the bolt 1 when the latter is forced outwardly from the bolt housing into the keeper 11.

When the door D is closed and the bolt 1 is lodged in the keeper 11, the door may be unlocked, or the bolt ejected from the keeper, by suitable operating means which may be the usual door knobs 21 and 22. These knobs are connected by a square spindle 23 which extends through a transverse hole D² in the door inwardly from the hole D¹ in which the ejector housing 13 is located. The knobs 21 and 22 and the spindle 23 are rotatably mounted on the escutcheon plates 24 and 25 at the opposite sides of the door. The spindle 23, which may be of square cross-section, is provided with a lock-operating crank portion 23^a which may be located in the middle between the opposite sides of the door. This crank portion is connected with the ejector by means of a tumbler 26 which has a thrust plate 26^a at its outer end and a small diameter shank 26^b which extends into the rear end of the hollow shank 14^b of the ejector 14. The thrust plate is normally held against the inner side of the throw portion 23^a of the crank by means of a compression spring 27. This spring is positioned around the shank 14^b and between the inner shoulder of the wall 13^b and the adjacent side of the thrust plate 26^a. The spring is centered on the latter plate by means of a boss 26^c, concentric with the shank 26^b, and is of the same diameter as the stop-collar 14^c. The inner portion of said stop collar merges gradually with the inner end portion of the shank 14^b to prevent the outer end of the spring 27 from seating thereon. The spring 27 forces the crank inwardly and thereby centralizes the knobs, or holds the same in neutral positions.

When the spindle is rotated to unlock the door, that is, when the bolt 1 has forced the ejector inwardly, as shown in Fig. 2, the tumbler 26 will be forced outwardly against the action of the spring 27. As the tumbler is forced outwardly,

the forward side of the boss 26^c engages the inner end of the ejector simultaneously with the engagement of the end of the tumbler with the inner side of the ejector head 14^a. The outward movement of the tumbler is checked by the engagement of the outer side of the plate 26^a with the inner end of the tubular portion of ejector housing.

Each of the escutcheon plates 24 and 25 consists of concentric inner and outer discs a and b, the inner discs being fully designated, respectively, 24^a and 25^a in the drawing, and the outer discs, respectively, as 24^b and 25^b. Both of the inner discs a are secured to the corresponding sides of the door by screws 28 (the screws 28, for securing discs 25^a, only being shown).

The outer disc b, may be rotatable about the secured inner disc, and is intended primarily to cover the screws. The knobs are shown as 20 screwed onto the spindle 23, and the inner ends of the knobs are seated in central holes of the outer discs b, and against shoulders c at the inner end of the holes. The outer discs b are thus held in position.

25 The mechanism above described is locked, that is, it may be held in such a position that the ejector 14 may not be forced outwardly by the knobs. A locking means for this purpose is shown as consisting of a locking member 31 which is 30 normally positioned against the inner side of the inner escutcheon plate 25. It is provided with a transverse slot 31^a which receives the spindle 23. The locking member has a downwardly extending portion 31^b which is provided with an arm 32 which extends outwardly through the escutcheon plate 25 and is provided at its outer end with a button 32^a. When the button is drawn outwardly the spindle 23 is permitted to rotate, but when it is forced inwardly, as shown by dotted lines in Fig. 2, it straddles the innermost crank arm 23^b, (the crank arms supporting the throw portion 23^a) preventing the spindle from rotating, and thereby preventing the opening of the lock from the opposite side.

40 An opening 25^d may be provided in the escutcheon plate 25, in line with the arm 32, or in such relation with respect to the locking member 31, that a suitable instrument inserted in such hole, may force the locking member free of the crank 45 arm to permit the knobs to be rotated. Or, if desired, a permanent unlocking rod (not shown) may be provided in the hole 25^d.

45 Though I have shown and described a particular construction, combination, and arrangement 50 of parts and portions, I do not wish to be limited to the same, but desire to include in the scope of my invention, the construction, combination, and arrangement, substantially as set forth in the appended claims.

60 I claim:

1. In a lock of the class described, a housing having a latch-receiving opening, a latch ejector movably mounted therein, one portion of the latter being normally held in the opening flush with the outside of the housing, a spring for resiliently holding said outer portion of the ejector in said flush position, and capable of allowing the ejector to be forced inwardly through the opening, and a rotatable spindle extending transversely 65 with respect to the housing for forcing the ejector outwardly with the rotation of the spindle.

2. In a lock of the class described, a housing having a latch-receiving opening, a latch ejector movably mounted therein, one portion of the latter being normally held in the opening flush

with the outside of the housing, a spring for resiliently holding said outer portion of the ejector in said flush position, and capable of allowing the ejector to be forced inwardly through the opening, a rotatable operating member having an axial offset, a tumbler movably mounted in the housing, a spring between the housing and the tumbler for forcing the latter toward the offset, said tumbler being capable of being forced, by the operating member, toward the ejector for forcing the latter outwardly after being forced inwardly from its flush position.

3. In a lock of the class described, a housing having a latch-receiving opening, a latch ejector movably mounted therein, one portion of the latter being normally held in the opening flush with the outside of the housing, a rotatable operating spindle member for positively forcing the ejector outwardly, and spring means for resiliently holding said outer portion of the ejector in said flush position and the operating member in a neutral rotating position.

4. In a lock of the class described, a housing having an outer face, a longitudinal bore inwardly from the face, and a shoulder at the inner portion of the bore, an ejector having a head reciprocally mounted in the outer portion of the bore, normally flush with the face but shiftable inwardly, said ejector having a tubular shank extending inwardly into the bore and beyond the shoulder, the inner portion of the shank having an abutment engageable with the inner side of the shoulder when the head is flush with the face of the housing, a spring in the bore around the shank and between the head and the front side of the shoulder for resiliently forcing the ejector to its outer position, an operating spindle having an axial offset, a tumbler having a head engageable with the offset and having a shank extending into the inner end of the ejector shank, and a spring between the shoulder and the tumbler head for normally forcing the tumbler head to engage the offset of the spindle.

5. In a lock of the class described, a plastic housing having a strike plate portion and a tubular portion extending backwardly therefrom, said tubular portion having a longitudinal bore open at its outer end through the strike plate portion, the inner portion of the bore having an annular restricted portion forming a shoulder, a plastic ejector mounted in the housing, said ejector having an enlarged head retractible into the outer portion of the bore and having a shank reciprocally mounted in the annular shoulder, the inner portion of the ejector shank having a collar for limiting the outward movement of the ejector, and a compression spring around the ejector shank and between the head of the ejector and the front side of the shoulder, said spring normally forcing the collar against the rear side of the shoulder and the head of the ejector flush with the outer face of the strike plate portion of the housing.

6. In a lock of the class described, a plastic housing having a strike plate portion and a tubular portion extending backwardly therefrom, said tubular portion having a longitudinal bore open at its outer end through the strike plate portion, the inner portion of the bore having an annular restricted portion forming a shoulder, a plastic ejector mounted in the housing, said ejector having an enlarged head retractible into the outer portion of the bore and having a shank reciprocally mounted in the annular shoulder, the inner portion of the ejector shank having a col-

lar for limiting the outward movement of the ejector, a compression spring around the ejector shank and between the head of the ejector and the front side of the shoulder, said spring normally forcing the collar against the rear side of the shoulder and the head of the ejector flush with the outer face of the strike plate portion of the housing, an operating member having an offset portion, a plastic tumbler having a wide head and a shank, the shank being reciprocally mounted in the ejector shank, and a compression spring positioned around the tumbler shank and between the shoulder and the head for normally forcing the head against the offset portion, the end of the tumbler shank and the head engaging respectively the ejector head and the inner end of the ejector shank when the tumbler is forced outwardly by the operating member.

7. In a lock of the class described, a housing having an outer face, a longitudinal bore inwardly from the face, and a shoulder at the inner portion of the bore, an ejector having a head reciprocally mounted in the outer portion of the bore, normally flush with the face but shiftable inwardly, said ejector having a tubular shank extending inwardly into the bore and beyond the shoulder, the inner portion of the shank having an abutment engageable with the inner side of the shoulder when the head is flush with the face of the housing, a spring in the bore around the shank and between the head and the front side of the shoulder for resiliently forcing the ejector to its outer position, an operating member in the housing, a tumbler operatively engaging the operating member and provided with a shank extending into the inner end of the ejector shank, and a spring between the shoulder and the extended end of the tumbler for normally forcing the latter into operative engagement with the operating member.

8. In a lock of the class described, a housing having a strike plate portion and a tubular portion extending backwardly therefrom, said tubular portion having a longitudinal bore open at its outer end through the strike plate portion, the inner portion of the bore having a restricted portion forming a shoulder, an ejector mounted in the housing, said ejector having an enlarged head retractible into the outer portion of the bore and having a shank extending reciprocally through the shoulder, the inner portion of the ejector shank having a collar for limiting the outward movement of the ejector, and a compression spring around the ejector shank between the head thereof and the front side of the shoulder, said spring normally forcing the collar against the rear side of the shoulder and the head of the ejector flush with the outer face of the strike plate portion of the housing.

9. In a lock of the class described, a housing having a strike plate portion and a tubular portion extending backwardly therefrom, said tubular portion having a longitudinal bore open at its outer end through the strike plate portion, the inner portion of the bore having a restricted portion forming a shoulder, an ejector mounted in the housing, said ejector having an enlarged head retractible into the outer portion of the bore and having a shank extending reciprocally through the shoulder, the inner portion of the ejector shank having a collar for limiting the outward movement of the ejector, a compression spring around the ejector shank between the head of the ejector and the front side of the shoulder, said spring normally forcing the collar

against the rear side of the shoulder and the head of the ejector flush with the outer face of the strike plate portion of the housing, an operating member having an offset portion, a tumbler having a head and a shank, the shank being reciprocally mounted in the ejector shank, and a compression spring positioned around the tum-

bler shank between the shoulder and the head for normally forcing the head against the offset portion of the operating member, the head of the tumbler engaging the inner end of the ejector shank when the tumbler is forced outwardly by the operating member.

HARRY E. FENDRING.
